HOT-WATER HEATER

William N. O'Malia, Oakland, Calif., assignor of
one-half to Clifford A. Hatch, Oakland, Calif.

Application September 27, 1947, Serial No. 776,573

4 Claims. (Cl. 122--161)

1

This invention relates to hot water heaters and has for its principal object the provision of a heater adapted for extreme economy of fuel.

I accomplish this result by the device illustrated on the accompanying drawings, in which:

Figure 1 is a vertical transverse section of my improved heater taken on line 1—1 of Figure 2;

Figure 2 is a plan view, partly broken away, of the heater shown on Figure 1.

Referring to the drawing in detail, my heater comprises a cylindrical water container, 5, having a vertical flue 6 passing through the center thereof. A plurality of relatively smaller flues 7 are spaced around the central flue 6 and communicate with a space 8 formed between the top 9 of the container 5 and the top 10 of an insulated jacket 11 surrounding the container 5.

The jacket 11 comprises an outer and inner lining having the intervening space packed with heat insulating material 12. It tightly surrounds the container 5 and extends above and below the same, to form the aforementioned space 8, and the firebox 13 under the container 5.

Telescopically mounted in the upper end of the central flue 6 is a close fitting pipe 14 which extends upwardly through the space 8 and through a relatively large concentric opening 15 in the top 10 of the jacket 11. An annular plate 16 is attached to the pipe 14 near the upper end thereof, and is of a larger diameter than the opening 15. This combination of plate 16 and pipe 14 serves the dual function of sealing the flue 6 from the space 8, and sealing the space 8 from the opening 15 when the plate 16 is seated on the top 12 of the jacket 11. The pipe 14 is adapted to function as a permanent seal while the plate 16 acts as a damper and cut-off for the flues 7.

A gas ring 17 mounted in the firebox 13 has, located above it, a bimetal or other suitable thermo-responsive device 18 adapted to raise and lower a centrally disposed vertical rod 19 which is attached to the upper end of pipe 14 by means of a cross-bar 20.

A concentric smoke casing 21 is fitted on the top 12 of the housing 11, and is provided with a circular upstanding flange 22 for engagement with a conventional flue pipe, not shown.

Fuel is furnished to the ring 17 through a thermostatically controlled valve T which has its element 23 extending into the interior of the container 5. The valve T is bypassed by a pilot light 24, to ensure flame to the fuel passing through ring 17.

The inlet and outlet pipes to the container 5 and the firebox door have not been indicated, as

2

they form no part of the novel features of the present invention.

When the heater is lit, the element 23, being surrounded by cold water, allows free flow of gas through the valve T. This in turn results in a maximum functioning of the element 18 to raise the damper 16 and allow the hot gases to pass through the flues 7, thus utilizing the maximum heating surface of the device. As the water in 10 the container 5 approaches the desired temperature, the valve T functions to restrict the flow of fuel to the ring 17, and as the flame gets lower, the element 18 allows the damper 16 to lower and eventually close the opening 15. The pilot light 15 stands in readiness in case the gas is completely shut off and later turned on by the action of the valve.

It will be apparent that when the water is brought up to the desired temperature, a temperature differential will exist between the upper space 8 and the firebox 13 which would result in a continuous circulation of cold air through the flues 7. I have, therefore, provided the automatic damper to eliminate this undesirable condition while still retaining the efficient feature of a tubular heater.

From the foregoing it will be apparent that I have devised a heater of high thermal efficiency which is capable of quickly bringing water to the desired temperature, and one which will maintain the temperature of the water with a minimum consumption of fuel.

While I have disclosed a preferred embodiment of my invention it should be understood that modifications may be made within the spirit and scope of the appended claims.

I claim:

1. A water heater comprising a drum for reception of water to be heated substantially surrounded by an insulating jacket, a firebox within said jacket immediately subjacent said drum, a first smoke space within said jacket adjacent said drum, a second smoke space adjacent said first smoke space and in communication therewith by means of a valve port, a primary flue in communication with said firebox and said second smoke space, a secondary flue in communication with said firebox and said first smoke space and in heat exchange relation with said water in the drum, said primary flue including a valve member arranged to open and close said valve port on axial movement of a portion of said primary flue whereby said secondary flue may be automatically placed in and out of communication with said 45 second smoke space.

2. A water heater comprising a drum substantially surrounded by an insulating jacket, a firebox within said jacket immediately subjacent said drum, a first smoke space within said jacket adjacent said drum, a second smoke space adjacent said first smoke space and in communication therewith by means of a valve port, a primary flue in communication with said fire box and said second smoke space, a secondary flue in heat exchange relation with the water to be heated and in communication with said firebox and said first smoke space, said primary flue including a portion telescopically mounted thereon for axial movement, a valve associated with said portion and movable in one of said smoke spaces whereby said valve may be automatically moved to open or close said valve port.

3. A water heater comprising a drum surrounded by an insulated jacket, said jacket extending above and below said drum to form a smoke space and a firebox respectively, said smoke space having an opening communicating with a second smoke space, a flue extending from said firebox through said opening and communicating with said second mentioned smoke space, a passage extending from said firebox in heat exchange relation with the water in said drum and in communication with said first mentioned smoke space, said flue having an axial movable section mounted in the upper end thereof, and a damper operatively associated with said section arranged to automatically regulate the size of said opening upon movement of said section.

4. A water heater comprising a shell-like member for reception of water to be heated, means immediately below said member forming a firebox and means immediately above said member forming a first smoke space, said first smoke space having a port therein communicating with a second smoke space, a primary flue extending through said member in heat exchange relation with the water therein and in flow communication with said firebox and said second smoke space, a secondary flue extending through said member in heat exchange relation with the water therein and in flow communication with said firebox and said first smoke space, an axially movable valve member interposed between said first and second smoke spaces, said valve member in closed position cutting off flow communication between said spaces, and means for raising and lowering said valve whereby said secondary flue may be automatically placed in and out of communication with said second smoke space.
